FIG. 19

FIG. 20

FIGURE 1 is a side elevation of a camera, or the like, showing my new design;

FIG. 2 is a front view thereof;

FIG. 3 is a rear view thereof;

FIG. 4 is a side elevation of the camera of FIG. 1, disclosing the opposite side;

FIG. 5 is a side elevation of a second embodiment of the camera, or the like, showing my new design;

FIG. 6 is a front elevation thereof;

FIG. 7 is a rear elevation thereof;

FIG. 8 is a side elevation thereof, disclosing the opposite side from that of FIG. 5;

FIG. 9 is a side elevation of a third embodiment of the camera, or the like, showing my new design;

FIG. 10 is a front elevation thereof;

FIG. 11 is a rear elevation thereof;

FIG. 12 is a side elevation thereof, disclosing the opposite side than that of FIG. 9;

FIG. 13 is a side elevation of a fourth embodiment of the camera, or the like, showing my new design;

FIG. 14 is a front elevation thereof;

FIG. 15 is a rear elevation thereof;

FIG. 16 is a side elevation thereof, disclosing the opposite side than that of FIG. 13;

FIG. 17 is a side elevation of a fifth embodiment of the camera, or the like, showing my new design;

FIG. 18 is a front elevation thereof;

FIG. 19 is a rear elevation thereof; and

FIG. 20 is a side elevation thereof, disclosing the opposite side than that of FIG. 17.

The tops and the bottoms are substantially identical in all embodiments and are plain and unornamented.

I claim:

The ornamental design for a camera or the like, as shown and described.
